Primary Examiner — Lauren R Calve(74) *Attorney, Agent, or Firm* — Lerner, David, Littenberg, Krumholz & Mentlik, LLP(57) **CLAIM**

The ornamental design for a packaging container, as shown and described.

DESCRIPTION

FIG. 1 is a perspective view of a packaging container.

FIG. 2 is a front elevation view thereof.

FIG. 3 is a rear elevation view thereof.

FIG. 4 is a right side elevation view thereof. The left side view is omitted because the left side view is mirror image of the right side view.

FIG. 5 is a top elevation view thereof.

FIG. 6 is a bottom elevation view thereof; and,

FIG. 7 is a perspective view with the lid closed.
